UNITED STATES PATENT OFFICE

RUSSELL B. TWEED AND CLAYTON WATSON, OF ST. PETERSBURG, FLORIDA

AIRCRAFT SKID SHOE

Application filed November 25, 1930. Serial No. 498,136.

This invention relates to skid shoes for aircraft and is especially designed for use as a tail skid shoe for an airplane.

It is the general practice to provide skid shoes for this purpose which are made of metal, such as iron or steel. These metal shoes wear exceedingly fast due to frictional contact with the ground, the ground usually being of an abrasive character which rapidly wears the metal even where high speed steel is used for a shoe.

It is the purpose of the present invention to provide a shoe whose ground engaging surface is harder than metal, and will cut such material as sand, brick, stone, glass or even high speed steel, so that the shoe will cut or grind into whatever surface it comes in contact with, instead of being cut, so that the life of the shoe will be materially increased. In addition, an increased gripping action will result, as the shoe will cut or grind into the ground and thus resist movement thereover.

Another object of the invention is to provide a skid shoe, which in addition to the above and other advantageous features, is simple in construction, reliable and efficient in use, and may be made at a relatively low cost.

With the above and other objects in view, the invention further includes the following novel features and details of construction, to be hereinafter more fully described, illustrated in the accompanying drawing and pointed out in the appended claims.

In the drawing:

Figure 1 is a side elevation showing the tail portion of an airplane with the invention applied.

Figure 2 is a bottom plan view of the skid shoe.

Figures 3 and 4 are sectional views taken respectively on the lines 3-3 and 4-4 of Figure 2.

Referring to the drawing in detail wherein

like characters of reference denote corresponding parts, the reference character 10 indicates a holder which forms a part of the shoe. This holder is made of metal and is provided with inwardly and downwardly inclined side and end walls. These walls are reinforced by right angularly arranged, transversely wedge-shaped ribs 11 and 12. These ribs taper upwardly and together with the inclined walls provide a number of separate compartments 13, the walls of which incline inwardly and downwardly. The front wall of the holder is preferably downwardly and inwardly curved as shown at 14 so as to provide a runner-like portion. The top 15 of the holder is provided with spaced front and rear threaded sockets 16 for the reception of bolts or screws 17, the latter serving as a means of attachment to an arm 18 which is carried by the tail portion 19 of an airplane.

The compartments 13 are filled with a non-metallic abrasive material 20 which is preferably composed of a non-metallic abrasive substance such as ground emery and a rubber binder. Other non-metallic substances may be used such as concrete, porcelain and the like, the purpose being to provide a non-metallic substance which will cut into the ground or other landing surface, instead of being cut. Wear therefore will be upon the landing surface or ground instead of upon the shoe. In addition, the action of the shoe cutting into the landing surface will act to retard the travel of the shoe, so that a braking action will be present.

The material 20 may be provided with metal rods 21 or other reinforcing elements so as to bind together more effectually the composition within the compartments 13.

The invention is susceptible of various changes in its form, proportions and minor details of construction and the right is herein reserved to make such changes as properly fall within the scope of the appended claim.

Having described the invention what is claimed is:-

An aircraft skid shoe comprising a hollow holder open at its lower side and having interior side wall surfaces converging toward said open side and a filling of non-metallic material having metallic reinforcing binding elements fitting snugly against the converging wall surfaces of the shoe, the lower surfaces of the filling being flush with the lower edges of the body.

10 In testimony whereof we affix our signatures.

RUSSELL B. TWEED.
CLAYTON WATSON.
